Application February 17, 1953, Serial No. 23,653

Term of patent 14 years

(Cl. D83—1)

To all whom it may concern:

Be it known that we, Robert P. Vuillemenot and Melvin E. St. Clair, respectively, citizens of the United States, residing at 482 Windsor Road, Borough of River Edge, county of Bergen, State of New Jersey, and 272B South Marshall Street, city and county of Hartford, State of Connecticut, have invented a new, original, and ornamental Design for a Dropper for the Ears, Eyes, Nose or the like, of which the following is a specification, reference being had to the accompanying drawing, forming a part hereof.

Fig. 1 is a top plan view of a dropper for the ears, eyes, nose or the like embodying our new design;

Fig. 2 is a side elevation view of the dropper, the opposite side of which is identical therewith; and

Fig. 3 is a view similar to Fig. 2 but with the cover removed from the container portion.

We claim:

The ornamental design for a dropper for the ears, eyes, nose or the like, as shown and described.

ROBERT P. VUILLEMENOT.
MELVIN E. ST. CLAIR.
